US00D968038S

(12) **United States Design Patent** (10) **Patent No.:** **US D968,038 S**
Li (45) **Date of Patent:** **** Oct. 25, 2022**

(54) **RETRACTABLE LEASH**

(71) Applicant: **DONGGUAN SHENGHE PLASTIC TECHNOLOGY CO., LTD.**,
 Dongguan (CN)

(72) Inventor: **Jiaxin Li**, Maoming (CN)

(73) Assignee: **DONGGUAN SHENGHE PLASTIC TECHNOLOGY CO., LTD.**,
 Dongguan (CN)

(**) Term: **15 Years**

(21) Appl. No.: **29/794,879**

(22) Filed: **Jun. 15, 2021**

(30) **Foreign Application Priority Data**

Dec. 31, 2020 (CN) 202030827762.5

(51) **LOC (13) Cl.** **30-04**

(52) **U.S. Cl.**

USPC **D30/153**

Primary Examiner — Kendra Leslie Hamilton

(57) **CLAIM**

The ornamental design for a retractable leash, as shown and described.

DESCRIPTION

FIG 1 is a perspective view of a retractable leash showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged, perspective view of detail “9”, identified in FIG. 2.

The broken lines in the drawings depict portions of the retractable leash that form no part of the claimed design.

1 Claim, 9 Drawing Sheets
